UNITED STATES PATENT OFFICE.

LOUIS V. ARONSON, OF NEWARK, NEW JERSEY.

TALKING-TOY MECHANISM.

1,140,647.

Specification of Letters Patent. Patented May 25, 1915.

Application filed September 19, 1914. Serial No. 862,425.

To all whom it may concern:

Be it known that I, LOUIS V. ARONSON, a citizen of the United States, and a resident of Newark, in the county of Essex and State 5 of New Jersey, have invented certain new and useful Improvements in Talking-Toy Mechanism, of which the following is a specification.

The invention relates to improvements in 10 so-called talking toys, and more particularly to mechanism for controlling the character of the sound to be emitted thereby.

It has for its object to simplify such mechanism and reduce its cost, as well as to 15 render the said mechanism more positive in its action and less likely to operate unsatisfactorily or become totally inoperative under the rough treatment to which toys of this character are generally subjected.

20 The nature of the invention will be best understood when described in connection with the accompanying drawings, in which—

Figure 1 is a plan of the improved mechanism adapted for emitting the desired 25 sounds; Fig. 2 is a front elevation thereof; and Fig. 3 is an end elevation.

Similar characters of reference designate corresponding parts throughout the several views.

30 Referring to the drawings, 10 designates a bellows, 11 being the base member thereof and 12 the movable member and the said members being normally held in distended position by means of a spring 13, as is well 35 understood. The bellows is adapted to be suitably secured in position within the body of the toy (not shown) and the movable member actuated by pressing upon some portion of the toy, all of which is well understood and forms no part of the present 40 invention, which has for its object the control of the character and duration of the sound emitted when the said bellows is being compressed. To the upper surface of 45 the movable member 12 of the bellows there is attached the usual reed pipe 15 which communicates with the interior thereof and one end of which extends into a sound box 16 provided with an orifice 17 permanently 50 open to the atmosphere and with a second orifice 18 normally closed by means of a flap 19 pivotally mounted upon the top of said box 16. By opening this latter orifice, through the movement of the said flap 19, 55 the character of the sound emitted will be

varied, as is well understood; and the duration of such variation as well as the particular succession of the sounds may be controlled to suit the desired toy. To operate the said flap, a control piece or member 20 is pivoted to the end of base member 11 of the bellows and extends upwardly and slightly beyond the upper and movable member 12 thereof. At its upper end, it is connected by means of a link 21 to the said flap 19, whereby by moving outwardly said control piece the flap may be raised. Normally, however, the flap is maintained in position to close the orifice 18 as by means of a spring 22 bearing thereon. The inward motion of the control piece, to admit of the proper closing of the orifice 18, is arrested by the movable member 12 of the bellows or, preferably, by an actuating piece or member 23 which is attached thereto and is arranged transversely to said control piece to coöperate with the same. The latter, moreover, is provided with a series of projections 24 and 25, for example two, arranged between the top and bottom and which may be 80 formed by bending inwardly the said piece. These projections, upon engaging the actuating piece 23 as the bellows is compressed, are adapted to throw the control piece 20 outwardly, as indicated in dotted lines, Fig. 85 2. As control piece 20 is thus moved, flap 19 is, through link 21, correspondingly raised and will effect the desired variation in the character of the sound emitted; and the duration of this new tone will depend 90 upon the relative length of the various projections 24 and 25.

A very simple and effective mechanism is hereby afforded for a positive control of the sound emitted; and, moreover, the same is 95 sufficiently substantial to withstand the usual rough treatment encountered by toys in which such mechanism is employed.

I claim:

1. Sound controlling device for talking 100 toys, comprising: a reed pipe or the like provided with an orifice, and a suitable bellows carrying said reed pipe and adapted to operate the same; a spring pressed flap normally closing said orifice; a control piece 105 pivotally attached to the stationary member of said bellows and provided with inwardly directed projections; an operating rod to co-operate therewith and attached to the movable member of said bellows transversely to 110

said control piece; and a link connecting the free end of said control piece with said flap.

2. Sound controlling device for talking toys, comprising: a suitable bellows, and a 5 spring attached at the sides of the top and bottom of said bellows and normally distending the same; a reed pipe or the like provided with an orifice and adapted to be operated by the said bellows, being carried 10 by the top of the same; a spring pressed flap normally closing said orifice; a control piece pivotally attached at one end to the front of the bottom member of said bellows and provided with inwardly directed projections; 15 an operating rod to coöperate therewith and

attached to the front of the top member of said bellows transversely to said control piece; and a link pivotally attached at one end to the other end of said control piece and pivotally attached at its other end to the said flap and extending over the top of the bellows.

Signed at Newark, in the county of Essex, and State of New Jersey, this 18th day of September A. D. 1914. 20

LOUIS V. ARONSON.
